COMBINED DISPENSING SPOUT AND CAP THEREFOR

Mark K. Dresden, Media, Pa.

Application June 9, 1952, Serial No. 20,105

Term of patent 14 years

(Cl. D58—26)

To all whom it may concern:

Be it known that I, Mark K. Dresden, a citizen of the United States, residing at Providence Road, Upper Providence Township, Delaware County, Media, Commonwealth of Pennsylvania, have invented a new, original, and ornamental Design for a Combined Dispensing Spout and Cap Therefor, of which the following is a specification, reference being had to the accompanying drawing, forming a part hereof.

Fig. 1 is a perspective view of a combined dispensing spout and cap therefor, showing my new design;

Fig. 2 is an enlarged side elevational view thereof;

Fig. 3 is an enlarged bottom plan view thereof; and

Fig. 4 is an enlarged top plan view thereof.

I claim:

The ornamental design for a combined dispensing spout and cap therefor, as shown.

MARK K. DRESDEN.
